CLAIM

What is claimed is the ornamental design for a post mounting bracket, as shown and described.

DESCRIPTION

FIG. 1 is a front top perspective view showing a post mounting bracket of Applicants' invention.

FIG. 2 is a rear bottom perspective view of the post mounting bracket of FIG. 1.

FIG. 3 is a front elevation view of the post mounting bracket of FIG. 1, the rear elevation view being an identical mirror image thereto.

FIG. 4 is a right side elevation view of the post mounting bracket of FIG. 1, the left side elevation view being an identical mirror image thereto.

FIG. 5 is a top plan view of the post mounting bracket of FIG. 1; and,

FIG. 6 is a bottom plan view of the post mounting bracket of FIG. 1.

The broken line showing of the two large holes on the base flanges and the six smaller holes on the upper flanges is included for the purpose of illustrating portions of the post mounting bracket and forms no part of the claimed design.
